Primary Examiner — Nathan M Johnston(74) *Attorney, Agent, or Firm* — FisherBroyles, LLP;
Jason P. Mueller(57) **CLAIM**

The ornamental design for a slide deck, as shown and described.

DESCRIPTION

FIG. 1 is a top plan view of the slide deck, featuring a dotted line shown for reference with respect to FIG. 3;

FIG. 2 is a top perspective view of the slide deck, featuring a dotted line shown for reference with respect to FIG. 4; FIG. 3 is a sectional view of the slide deck, taken along the dotted line as shown in FIG. 1;

FIG. 4 is a sectional view of the slide deck, taken along the dotted line as shown in FIG. 2;

FIG. 5 is a bottom perspective view of the slide deck;

FIG. 6 is an exploded view of the slide deck, taken from a top perspective view; and,

FIG. 7 is top perspective view of the slide deck, while the slide deck is deployed.

The dotted lines shown in FIG. 1 and FIG. 2 are shown for purposes of illustration, and do not constitute part of the claimed design.
